UNITED STATES PATENT OFFICE.

SYDNEY JAMES BEDINGTON, OF LONDON, ENGLAND, ASSIGNOR TO ROY S. KNAGGS, OF NEW YORK, N. Y.

BUILDING CARD STRUCTURE AND BLANK FOR PRODUCING THE SAME.

Application filed May 17, 1926, Serial No. 109,696, and in Great Britain October 5, 1925.

The present invention has for its object to produce a building card structure and a blank in multiple form from which the structural units may be cut and bent into shape, and provided with means whereby the several units may be interlocked so that a plurality of superimposed and adjacent units when arranged and interlocked will produce pleasing and instructive architectural simulations, the parts of which are held together and the general form of which may be varied according to various architectural conceptions of the user. It is primarily intended of course as an amusing and pleasing toy for children.

The invention is illustrated in the accompanying drawings in which

Fig. 1 shows in perspective a plurality of units relatively positioned for connecting them with each other but disconnected.

Fig. 2 shows a blank from which a multiplicity of units may be cut.

Fig. 3 shows in a fragmentary detail and sectional view the manner of connecting adjacent units in building up an architectural structure.

Fig. 4 shows in perspective a simple form of architectural structure produced by coupling together a plurality of units.

Fig. 5 shows another form of blank from which the units may be cut.

Fig. 6 shows a fragmentary detail of adjacent superimposed units and illustrating the manner of connecting them.

Fig. 7 is a similar view showing in section the connection of a closing or side unit with other units.

Similar reference characters will be employed throughout the specification and drawings to designate corresponding parts.

The units are preferably made of cardboard of suitable weight, finish and flexibility, and preferably as shown in Figs. 2 and 5, a plurality of units will be formed in a single blank upon which will be printed, surface ornamentations 1, full lines 2, and dotted lines or scorings 3, the full lines indicating cutting lines and the dotted lines or scorings bending lines. The ornamentations or that portion of the blank included between folding lines will be substantially square, and in the blank shown in Fig. 2 square units 4 will be provided between the cutting lines 2, and such units will be pro-

vided with the slots 5 located within the margin and arranged parallel with each other and extending towards each other at the ends as indicated at 6. The slots 5 pass entirely through the blank and form locking tongues or tabs 7. In the form shown in Fig. 5 the units 4 are positioned between two of the ornamental blocks and bounded by folding lines or scores 3. Each of the units with the exception of the units 4 are provided with extensions 8 for a purpose to be hereinafter described. Each blank also will show cutting lines 2 for producing, when cut up, connecting units 9 for a purpose to be described.

When the blanks have been cut up on the cutting lines 2 and bent on the bending lines or scorings 3 there will be produced the building or structural units 4, 9, 10, 11 and 12. (See Fig. 1.) The units 9 of course are simply rectangular strips of cardboard relatively narrow and somewhat shorter than the distance between two sides of the squares formed by the cutting lines or the bending and scoring lines 3. The unit 10 has two square members 13 united by an angle or gable 14 formed by bending upon an intermediate scoring line 3 and having the inwardly projecting flanges 15 at the lower ends of the members 13. The units 11 will have an intermediate unit 4 carrying the locking tongues 7, two side members 16 depending therefrom with the inwardly bent flanges 17 at the lower ends. The unit 4 will be simply a square provided with locking tongues 7. The units 12 will be substantially square and provided along two of their opposite edges with inwardly turned flanges 18.

With the units or members cut out and bent along the folding or bending lines in the form shown in Fig. 1 they may be connected so as to produce the simple architectural structure as shown in Fig. 4 by forcing the flanges 15 of the unit 10 beneath the locking tongues 7 of the unit 4, and the flanges 17 of the unit 11 beneath the locking tongues 7 of the unit 4, and the flanges 17 of the lowermost unit 11 beneath the locking tongues 7 of the single unit 4. In order to close the sides of the units 11 the units 12 are connected by forcing the flanges 18 of such units beneath the outer ends of the flanges 17, and the adjacent surface of the

units 4. By so doing a construction like Fig. 4 will result. The units 9 are employed when it is desired to extend the architectural structure by adjacent structures as indicated in Fig. 3 where the units 9 are shown as spanning the joint or space between two architectural structures.

It is important to note that the slots 5 forming the locking tongues 7 are set inward 10 with relation to the edges of the unit 4 not only with regard to the longer portions 5 of such slots, but also with regard to the in-turned portions 6, so that there is practically an unbroken marginal extension projecting beyond the slots along all four sides of 15 the square producing clearance space between adjacent units into which the flanges of other units or the coupling units 9 may be inserted.

The locking tongues 7 also will be of such 20 width as to be able to receive a substantial portion of the inturned flanges 15, 17 and 18 and still leave the wall surfaces of the units and all adjacent units on a line with the wall surfaces of other units.

25 For convenience of reference the unit 10 may be referred to as a gable unit; the units 11 as block units; the units 12 as side closing units; and the unit 4 where separately formed, as a base unit.

30 The blanks from which the units are to be cut may be of any number, dependent upon the number of units contained in any set of units, and of varying size, as shown; and they may be packed as separate sheets or

they may be bound up in book form for convenience in packing and selling.

Having described my invention I claim:

1. A building card structure comprising card-board units each composed of a central member provided with locking tabs and 40 other members having in-turned flanges, the flanges of one unit engaged with the locking tabs of an adjacent unit, and side units provided with in-turned flanges along two of its opposed edges adapted to be received in 45 the space between the outer ends of the flanges and of adjacent units.

2. A building card structure comprising an integrally formed unit having a central member and members disposed at opposite 50 sides of said central member, all of said members being substantially uniform in size and shape, the outer members provided with an integral flange along one edge, said flanges of said outer members being opposed to 55 and parallel with each other, the central member provided wholly within its surface area with integrally formed, parallel, oppositely extending tabs to receive the flanges 60 of the outer members of an adjacent unit.

3. A building card structure comprising a unit having a central member and members disposed at the opposite sides of said central member, and having at their lower edges inwardly turned flanges, the central member being provided with integrally formed tabs 65 to receive the flanges of an adjacent member.

SYDNEY JAMES BEDINGTON.
